Inventor

Joseph Girard
By Chas. St. Burleigh - Attorney.

UNITED STATES PATENT OFFICE.

JOSEPH GIRARD, OF WORCESTER, MASSACHUSETTS.

INJECTOR OIL-BURNER.

SPECIFICATION forming part of Letters Patent No. 418,121, dated December 24, 1889.

Application filed April 14, 1888. Serial No. 270,629. (No model.)

To all whom it may concern:

Be it known that I, JOSEPH GIRARD, a citizen of the United States, residing at Worcester, in the county of Worcester and State of Massachusetts, have invented certain new and useful Improvements in Injector Oil-Burners, of which the following, together with the accompanying drawings, is a specification sufficiently full, clear, and exact to enable persons skilled in the art to which this invention appertains to make and use the same.

The object of my present invention is to provide an efficient, convenient, and economical apparatus for the combustion of liquid hydrocarbon in furnaces for heating steam-boilers and for other analogous purposes, the particular features of improvement and subject-matter claimed being hereinafter definitely specified.

20 In the drawings, Figure 1 is a longitudinal vertical section of a steam-boiler furnace illustrating the nature of my invention. Fig. 2 is a vertical transverse section at line *x* *x*, Fig. 3. Fig. 3 is a horizontal section at line 25 *y* *y*, Fig. 1. Fig. 4 is a longitudinal section showing details of the atomizing and injecting devices drawn to somewhat larger scale; and Fig. 5 is an inner end view of the injecting-tube.

30 Referring to parts, A denotes the main walls of the furnace, and B the boiler, which parts may be constructed and arranged in well-known manner, with the furnace-chamber C, pit *a'*, bridge-wall A', and grate or supporting bars *g*, disposed substantially as shown.

D indicates the tube or funnel through which the liquid hydrocarbon is injected or thrown into the furnace-chamber C. Said funnel is some two and one-half inches (more or less) in diameter, open at both ends, and of a length that will extend through the wall of the furnace and project within and without to the required distance, or as convenient 45 for attachment of pipes and facility of working. This funnel D is arranged in the end of the furnace, substantially as indicated. The outer end of the funnel-tube is preferably curved out of line with its axis, but may 50 be made straight, if in any instance desired.

E indicates the pipe through which the

liquid hydrocarbon is conducted from the tank E' or other source of supply and delivered to the interior of the funnel D. Said pipe E extends into the funnel D, as indicated, and has its delivery-orifice near the central axis thereof, as at *e*.

E² indicates the cock or valve for regulating the quantity of hydrocarbon delivered in a given time, and *e'* indicates a screw-nut for adjusting the position of the delivery end of said pipe.

F indicates the atomizer-nozzle or blast-pipe entering the funnel D parallel with its axis and at right angles to the pipe E, with 65 its exit-orifice *f* disposed in relation to the orifice *e* in such a manner that the blast through the orifice *f* will atomize or spray the liquid as it enters at *e* and project the spray forward through the funnel D into the furnace. A suitable cock or valve F' is provided for regulating and stopping off the flow or blast through the nozzle F.

H indicates a secondary blast-nozzle arranged below or near the nozzle F, preferably with its exit-orifice *h* slightly back from the orifice *f*, although this is not absolutely essential. The nozzle projects its blast in the same direction as the nozzle F, and its purpose is for augmenting the pressure or re-enforcing the action for driving forward the spray when a large quantity of hydrocarbon is being introduced from the pipe E—as, for instance, when it is desired to temporarily force the furnace beyond the normal working 85 condition, to quickly recover loss of steam-pressure, or to meet any unusual exigencies of service that may occur in practice. This nozzle is provided with a suitable cock or valve for stopping and regulating the blast 90 therethrough. The apparatus may be used either with or without the nozzle H.

Around the front or inner end of the injector-tube or funnel D, I provide an auxiliary annular blast-nozzle I or drip-preventer. 95 Said nozzle consists of a chamber or passage *i*, having a narrow annular opening I, that surrounds the extremity of the funnel D in the manner shown, said opening being directed in substantially the same direction as 100 the exit-orifice of the funnel. (See Fig. 4.) A passage or pipe I' connects the annular noz-

zle I with the main blast-pipe J, and a suitable valve or cock I² is provided for stopping and regulating the passage. The purpose of the nozzle I is to throw forward the flame and regulate its force; also to take care of any drops of liquid hydrocarbon that may collect on the interior of the funnel, and to project the same forward as spray into the furnace, and thus prevent liquid dripping from the end of the funnel. The pipe J connects with the steam-boiler B and serves for supplying steam to the several blast-nozzles F, H, and I. Said pipe is provided with a coupling-head J' for the attachment of a blower or air-pipe to facilitate the employment of air for the blast instead of steam when desired.

J² and J³ indicate valves for opening or closing the pipe J for the steam or air, as required.

By means of the valves H' and I² the relative force of the blast at the nozzles H and I can be controlled and varied for regulating the action to give a flame of greater or less intensity and force, as desired, while the quantity of hydrocarbon liquid supplied in a given time can be regulated by the cock E' in the delivery-pipe E.

The pipe J can, if desired, be carried through the furnace-chamber C, as indicated by dotted lines in Fig. 1, for superheating the steam for the blast. This, however, is a well-known practice in apparatus of this class, and I do not consider it an essential feature.

G indicates the fire-brick bed of the furnace; g, the supports therefor; K, the auxiliary lining-wall; m m', a flame-barrier, and K' K² K³ air-passages leading from the pit a' for delivering air into the combustion-chamber.

In the operation the liquid hydrocarbon, as it is delivered at the orifice e, is atomized by the strong blast of steam from the nozzle F, and is blown forward through the funnel D in the form of spray, together with a quantity of air which enters the open end of said funnel at d, and the projecting force is further augmented by the blast issuing from the annular nozzle I, thereby injecting the vaporized hydrocarbon into the furnace-chamber, where it is ignited and consumed as it mingles with the air entering through the passages K, the flame being broken up and distributed by the barrier, complete combustion being effected as the gases pass along the under side of the boiler in an economical and efficient manner. When it is desired to inject a large proportion of hydrocarbon, the auxiliary blast from the nozzle H is turned on more or less in addition to the nozzle F and the cock E' opened to deliver the quantity desired.

Among the advantages incident to my invention may be named its economy and effi-

cency in the combustion of hydrocarbon liquid, complete atomization and the prevention of drip from the injector-funnel, complete and prolonged combustion throughout the length of the fire-chambers, convenience and facility in the perfect control and regulation of the quantity and intensity of the fire as desired, and the practical adaptation of the apparatus for inexpensive application to boiler-furnaces which are now in use.

I am aware that in apparatus for burning liquid hydrocarbon it is a well-known practice to atomize the hydrocarbon and inject it into the furnace by a forced blast of steam or air; hence it will be understood that I do not broadly claim apparatus for effecting such operation irrespective of the construction and arrangement thereof.

I am also aware that a barrier within the furnace-chamber has heretofore been employed in combination with a hydrocarbon-burner, but of different construction from my improved barrier hereinbefore described.

What I claim as of my invention, and desire to secure by Letters Patent, is—

1. In an injector oil-burner, the combination, with the injector-funnel having means, substantially as described, for producing from liquid hydrocarbon an atomized vapor within the tube of said funnel, of an annular auxiliary blast-nozzle mounted upon and surrounding the exit extremity of said injector-funnel, substantially even therewith, and provided with an exit-opening that delivers a blast in the same direction, or substantially so, as the exit of said funnel, and a pipe externally of said funnel for supplying steam-blast pressure to said auxiliary nozzle, as and for the purpose set forth.

2. The combination of the injector-funnel, the oil delivery and atomizing nozzles arranged therein near its outer end, relatively as shown, the annular chamber i, surrounding the inner end of said funnel and having the blast-opening I even with its inner extremity, the pipes J F to the atomizing-nozzle, and pipe I', leading to said annular chamber for supplying steam thereto, and the cocks F' and I² in the respective pipes for independently regulating the same, all arranged and operating substantially as shown and described.

3. The combination of the injector-funnel having the open ends, the hydrocarbon-liquid-delivery pipe, the atomizing blast-pipe, and the secondary blast-pipe, with their exit-openings within said funnel, and regulating-valves in each of said pipes for controlling the delivery of hydrocarbon, the atomizing-blast and secondary blast, respectively, all arranged substantially as and for the purpose set forth.

4. The combination, substantially as described, of the injector-funnel having the open ends, the hydrocarbon-delivery pipe,

the atomizing blast-pipe, the secondary blast-pipe, the annular blast-nozzle surrounding the inner extremity of said injector-funnel, the steam-supply pipes, and the stop-cocks or valves, respectively, disposed in said delivery-pipe, steam-supply and blast pipes, for controlling the passages through the respective pipes, all arranged and organized for operation as and for the purpose set forth.

Witness my hand this 31st day of March, 10
A. D. 1888.
